DESIGN FOR AN AEROPLANE

Robert H. Brown, Indianapolis, Ind.

Application January 31, 1942, Serial No. 105,538

Term of patent 14 years

To all whom it may concern:

Be it known that I, Robert H. Brown, a citizen of the United States and a resident of Indianapolis, county of Marion, and State of Indiana, have invented a new, original, and ornamental Design for an Aeroplane, of which the following is a specification, reference being had to the accompanying drawing, forming part thereof.

In the drawing

Fig. 1 is a top plan view of an aeroplane showing my new design.

Fig. 2 is a front elevational view of the aeroplane.

Fig. 3 is a side elevational view.

Fig. 4 is a vertical sectional view taken on line 4—4 of Fig. 2 and in the direction of the arrows.

The dominant features of the aeroplane of my design are shown in full lines in the drawing.

I claim:

The ornamental design for an aeroplane, as shown and described.

ROBERT H. BROWN.
